[57] **CLAIM**

The ornamental design for a combined toothbrush and toothpaste dispenser with cap, as shown.

DESCRIPTION

FIG. 1 is an exploded front elevational view of the combined toothbrush and toothpaste dispenser with cap of the present invention;

FIG. 2 is a rear elevational view of the combined toothbrush and toothpaste dispenser with cap of FIG. 1;

FIG. 3 is a left side elevational view of the combined toothbrush and toothpaste dispenser with cap of FIG. 1;

FIG. 4 is a right side elevational view of the combined toothbrush and toothpaste dispenser with cap of FIG. 1;

FIG. 5 is an enlarged top plan view of the combined toothbrush and toothpaste dispenser with cap of FIG. 1; and,
FIG. 6 is an enlarged plan view of the combined toothbrush and toothpaste dispenser with cap of FIG. 1.

The top of the toothbrush portion neither shown in the drawing nor described in the specification forms no part of the claimed design.
